[57] CLAIM

The ornamental design for a magnetic water conditioner, substantially as shown and described.

DESCRIPTION

FIG. 1 is a perspective view taken from the top, front and left end of a magnetic water conditioner showing my new design;

FIG. 2 is a left end elevational view thereof;

FIG. 3 is a right end elevational view;

FIG. 4 is a top plan view;

FIG. 5 is a rear elevational view thereof; and

FIG. 6 is a bottom plan view.

*Fig. 2**Fig. 1**Fig. 3**Fig. 4**Fig. 5**Fig. 6*
